[57] CLAIM

The ornamental design for a ceiling mounted lighting panel, as shown and described.

DESCRIPTION

FIG. 1 is a bottom plan view of a ceiling mounted lighting panel showing my new design.

FIG. 2 is a side elevational view of the ceiling mounted lighting panel of FIG. 1.

FIG. 3 is an end elevational view of the ceiling mounted lighting panel of FIG. 1.

FIG. 4 is a bottom perspective view on a reduced scale thereof.

In the plan view of FIG. 1, the surface underlying the squares representing light emitting structures is of black color.
